UNITED STATES PATENT OFFICE.

FRED EKMAN, OF HONOLULU, TERRITORY OF HAWAII.

TURRET TOOL-HOLDER.

1,392,128.

Specification of Letters Patent. Patented Sept. 27, 1921.

Application filed April 3, 1918. Serial No. 226,448.

To all whom it may concern:

Be it known that I, FRED EKMAN, a citizen of the United States, residing at Honolulu, in the county of Honolulu and Territory of 5 Hawaii, have invented new and useful Improvements in Turret Tool-Holders, of which the following is a specification.

This invention relates to improvements in turret tool-holders for use in lathes and 10 shapers, the object of the invention being to provide an improved toolholder of this class which is adapted to hold a number of tools and to be readily adjusted so that any one of the tools may be used as required and thus 15 save the time required in changing the tools.

With the above and other objects in view, the invention consists in the construction, combination and arrangement of devices hereinafter described and claimed.

20 In the accompanying drawing:—

Figure 1 is a front elevation of the turret toolholder constructed and arranged in accordance with my invention.

Fig. 2 is partly an elevation and partly a 25 central sectional view of the same.

Fig. 3 is a detail sectional view of the same on the plane indicated by the line 3—3 of Fig. 1.

In accordance with my invention, the 30 standard 1 is provided with a frusto-conical recess 2 at one side, near its upper end, and with a polygonal counter recess 3, which communicates with the smaller end of the recess 2, said polygonal counter recess being 35 here shown as square.

The head 4 of the toolholder is circular and is provided with a plurality of radially arranged tool holding arms 5 which are here shown as four in number, one for each side 40 of the counter recess. On its rear side, the head is provided with a centrally arranged frusto-conical projection 6 which is adapted to fit in the recess 2, and also with a polygonal projection 7, which is adapted to fit in 45 the counter recess 3. The head is also formed or provided with a screw stem 8 which passes through an opening 9 at the center of the counter recess. A knurled lock nut 10 is threadedly engaged with the screw stem 50 and a washer 11 is interposed between the nut and the rear side of the standard so that the head may be secured firmly to the standard at any desired adjustment of the head.

Each arm 5 has an opening or socket 12 to 55 receive a tool and is also provided with a

clamping screw 13 which will hold the tool in place. In practice, different tools are secured in the arms of the head, and by first loosening the nut on the screw stem, the head can be partly withdrawn from the standard 60 a sufficient distance to release the projection 7 from the counter recess and can be then turned to bring any desired tool in position for use and can then be secured in such adjusted position by tightening the nut, and 65 thus causing the projection 7 to coact with the sides of the polygonal counter recess to effectually lock the head and prevent it from turning to any extent when the tool is in use.

While I have herein shown and described a 70 preferred form of my invention, I will have it understood that changes may be made in the form, proportion and construction of the several parts without departing from the spirit of my invention and within the scope 75 of the appended claim. The coacting sides of the projection and the polygonal recess also insure that the tool will be in the required position for use.

I claim:—

The combination with a standard provided with a frusto-conical recess and having a polygonal recess communicating with the converging end of said frusto-conical recess, of a circular head provided with a central 85 opening and having a plurality of transverse openings therein communicating with said central opening, a plurality of tool holding arms formed integrally upon diametrically opposite sides of said head, provided with 90 longitudinal openings therethrough communicating with the transverse openings in said head and having transverse threaded openings therein communicating with said longitudinal openings, a frusto-conical projection 95 formed integrally on said head and engaging said frusto-conical recess, a polygonal projection formed integrally with said frusto-conical projection and engaging said polygonal recess, a stem formed integrally 100 with said polygonal projection and exteriorly threaded throughout its length, a knurled lock nut engaging said threaded stem, a washer disposed on said stem between said nut and polygonal projection and engaging said standard, and set screws engaging the threaded openings in said tool holding arms.

In testimony whereof I affix my signature.

FRED EKMAN.
